UNITED STATES PATENT OFFICE.

RALPH A. DUFF, OF NEBRASKA CITY, NEBRASKA.

CARBURETER.

1,285,648.

Specification of Letters Patent. Patented Nov. 26, 1918.

Application filed February 12, 1916, Serial No. 77,941. Renewed June 1, 1918. Serial No. 237,834.

To all whom it may concern:

Be it known that I, RALPH A. DUFF, a citizen of the United States, residing at Nebraska City, in the county of Otoe and State 5 of Nebraska, have invented a new and useful Carbureter, of which the following is a specification.

This invention relates to carbureters of that type wherein the proportions of the 10 explosive mixture may be controlled by the operator to suit the load.

One of the objects of the invention is to provide a special starting jet with which is combined means for directing the explosive 15 mixture past the butterfly or throttle valve into the manifold portion of the carbureter.

A further object is to so dispose the air inlet relative to the gas jets or nozzle as to result in a more thorough breaking up of 20 the gas jets and the commingling of the gas with the air than has heretofore been possible.

Another object is to provide means whereby any possible leakage of gas from the 25 starting jet or nozzle is prevented while said jet or nozzle is cut out or is in inactive position.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, can be made within the scope of what is claimed, without departing from the spirit of the invention.

In the accompanying drawings the preferred form of the invention has been 40 shown.

In said drawings:—

Figure 1 is a side elevation of a carbureter embodying the present improvements.

Fig. 2 is a vertical longitudinal section 45 therethrough, parts being broken away.

Fig. 3 is a view partly in end elevation and partly in section.

Fig. 4 is a section on line A—B Fig. 2.

Fig. 5 is a perspective view of the fuel 50 valve.

Fig. 6 is a perspective view of the air inlet valve.

Referring to the figures by characters of reference 1 designates a float chamber having the usual float 2 for maintaining the fuel at a predetermined level. This float 55 chamber has an outlet 3 opening into a

valve casing 4 having a series of alining outlet ports 5. Communicating with and extending upwardly from one of the end 60 ports 5 is a starting nozzle 6, while additional nozzles 7 and 7' communicate with and extend upwardly from the remaining ports 5. Mounted for rotation within the casing 4 is a hollow cylindrical valve 8 which is in constant communication with the port of nozzle 6. One end of the valve 8 has a stem 9 extending therefrom and secured to a segmental gear 10. Formed in the valve 8 are ports 11 of different lengths 65 and extending in the direction of rotation of the valve, one of these ports 11 being provided for each port 5. One port 11 maintains nozzle 7' constantly in communication with outlet 3. The other ports 11 are 70 so positioned and proportioned that, during the rotation of the valve 8 in one direction, the ports 11 will be brought successively into communication with their respective ports 5 and with the fuel outlet 3 so that the nozzles 80 7 will be brought successively into communication with the outlet 3, each nozzle remaining in communication with the outlet 3 while the next adjoining nozzle is being placed in communication with said outlet. 85 Thus ultimately all of the nozzles 7 are in communication with the float chamber 1. When valve 8 is rotated in the opposite direction, all of the nozzles 7 are successively cut out of communication with the outlet 3, 90 nozzle 7' remaining in communication with said outlet, so as to constitute a low speed or idling nozzle.

The valve casing 4 is secured to the bottom of a mixing chamber 12 and the series 95 of nozzles 7 and 7' project upwardly into one end portion of this mixing chamber, said series of nozzles extending transversely of the chamber. The nozzle 6, however, does not extend into the mixing chamber 100 but, instead, projects into one end of a bypass 13 formed in one wall of the mixing chamber, this bypass having an outlet 14 between the butterfly or throttle valve 15 in the carbureter and the manifold end 16 of the carbureter. An air inlet opening 17 opens into the bypass 13 at one side of the nozzle 6 and a cylindrical valve 18 is mounted for rotation in the bypass and is adapted normally to close said bypass. The valve 110 18 is provided with separate passages 19 and 20. The passage 19 is adapted to aline with the bypass 13 when the valve is in one position, thus to permit the free circulation

of gas along the bypass from nozzle 6 to the outlet 14. The passage 20 is adapted, when valve 18 is in closed position, to establish communication between the back 5 portion of the bypass 18 and an air inlet opening 21 formed in the wall of the mixing chamber 12. Thus when valve 18 is closed atmospheric pressure is maintained within the back portion of the bypass 18 where the 10 nozzle 6 is located and, consequently, there is no danger of leakage of gas past the valve 18 as a result of the suction set up by the engine while in motion.

Arranged back of the mixing chamber 12 15 is a valve casing 22 which can be an integral part of the casing of the mixing chamber. This valve casing has one end open and also has a sight slot opening 23 in its back and mounted for rotation within the valve casing 2. This is a hollow cylindrical valve 24 open at one end and provided with a longitudinal port 25 which is preferably V-shaped. This port has an extension 25' at one end and back of the nozzle 7'. Extension 25' is constantly 20 in communication with one end of an outlet port 26 in the form of a slot extending transversely of the rear wall of the mixing chamber 12 approximately on a level with the upper ends of the nozzles 7 and 7'. Port 25 is so shaped and located that, during 25 rotation of valve 24 in one direction, one corner portion of the port 25 will first come into register with port 26 directly back of that nozzle 7 which is first brought into communication 30 with the gas outlet 3. During further rotation of valve 24 the area of the port 25 in communication with outlet port 26 increases gradually so that the amount of air supplied to the mixing chamber is increased, the sheet of air thus discharged into 35 the mixing chamber spreading from one side toward the other of the mixing chamber so that after the rotation of valve 24 has been completed, the sheet of air discharging into 40 the mixing chamber 12 will extend throughout the width of said mixing chamber and back of all of the nozzles 7 and 7'.

Valve 24 is provided at one end with a stem 27 to which is secured a segmental gear 50 28 constantly in mesh with the segmental gear 10. An arm 29 is formed with or secured to the segmental gear 28 and is connected, by a link 30, to one arm of a lever 31 secured to the stem of the throttle valve 15. The gears 10 and 28 are so proportioned that 55 when the throttle valve 15 is closed, the said gears will operate both of the valves 24 and 8 so as to completely close all but one end of the port 26 and all of the nozzles 7. When, however, the throttle valve 15 is partly 60 opened, the gears 28 and 10 will be actuated simultaneously to admit a small quantity of air directly back of the first nozzle

7 while the valve 8 will at the same time be given a slight movement so as to place the 65 first nozzle 7 in communication with the fuel outlet 3 in addition to nozzle 7'. Thus a small additional quantity of gas and air will be directed into the mixing chamber 12. Obviously as the throttle valve 15 is moved 70 still farther toward its full open position, more nozzles 7 are brought into communication with the outlet 3 and the supply of air to the port 26 is increased. Importance is attached to the fact that the sheet of air directed 75 into the mixing chamber passes thereto practically across the ends of the nozzles 7 and 7' and at right angles thereto with the result that as the gas leaves the nozzles it is thoroughly broken up by the air currents and a better mixture is thus obtained than would otherwise be the case.

Assuming that the throttle valve 15 is closed and it is desired to start the engine, the operator opens the valve 18 by any suitable means provided for that purpose. Thus the passage 19 is brought into alignment with the bypass 18, and when the engine is started, a rich mixture of gas and air will be directed thereto from the nozzle 6 and 80 the air inlet 17, this explosive mixture flowing along the bypass 18 and past the throttle valve 15 to the manifold. The throttle valve can then be gradually opened as before described and valve 18 closed.

What is claimed is:—

1. A carbureter including a mixing chamber, a float chamber associated therewith, valve casings, valves turning in the casings, nozzles rising from one valve casing into the 100 mixing chamber, one of said nozzles being normally in communication with the float chamber and the air port, and means for revolving the valves to successively admit fuel to and direct air across a number of or 105 all the nozzles.

2. A carbureter including a mixing chamber formed with an elongated air inlet port, a float chamber associated therewith, valve casings, an air control and a fuel control 110 valve, each turning in its respective casing, nozzles rising from one casing and extending into the mixing chamber and terminating before the air port, one of said nozzles being normally in communication with the 115 float chamber, and means for simultaneously turning the valves to successively admit fuel to and direct air across a desired number or all the nozzles.

In testimony that I claim the foregoing as 120 my own, I have hereto affixed my signature in the presence of two witnesses.

RALPH A. DUFF.
